UNITED STATES PATENT OFFICE.

EDMUND E. PECK, OF BROOKLYN, NEW YORK.

CARPET-SWEEPER.

SPECIFICATION forming part of Letters Patent No. 469,714, dated March 1, 1892.

Application filed March 9, 1891. Serial No. 384,243. (No model.)

To all whom it may concern:

Be it known that I, EDMUND E. PECK, a citizen of the United States, residing at Brooklyn, in the county of Kings and State of New York, have invented an Improvement in Carpet-Sweepers, of which the following is a specification.

This invention relates to that class of carpet-sweepers in which there is a central rotary brush receiving its motion from wheels at the ends of the box, the dust being delivered into pans that are pivoted and capable of being swung open for the discharge of such dust; and the invention relates to the combinations of devices hereinafter set forth.

In the drawings, Figure 1 is an end elevation, portions of the box and of the end frame being removed and in section to illustrate the construction of the sweeper. Fig. 2 is a plan view at one end of the sweeper, the parts being broken open in such a way as to show the internal construction, the brush being indicated in dotted lines; and Fig. 3 is a partial vertical section at the line $x-x$, Fig. 2. Fig. 4 is a diagram showing the levers and sweep-inclines detached.

The box itself is formed of ends A, with upper and side inclosures A' A², and the brush B occupies a central position in the sweeper, and the bristles of the brush are preferably applied in spiral lines around the central axis B', and there are journals 2 at the ends, which journals are received into the bearings in the end frames C. These end frames C are usually of metal, curved at their respective ends, and passing around and united by the screws 3 with the side portions A² of the sweeper-box, and there are spaces between the end frames C and the ends A of the box sufficient for the reception of the actuating-wheels, as indicated in Fig. 2. These actuating-wheels are of metal, as shown at D, and around each metal wheel is a tire 4, of flexible material—such as rubber—secured thereto by suitable cement or otherwise, and the periphery of the tire is roughened by diagonal corrugations crossing each other and forming projecting points in order that such roughened rubber tires may be more reliably acted upon by the carpet to rotate the wheels, and at the same time such rubber tires will rotate the brush by acting

upon the end pulleys E of such brush, these pulleys E being corrugated upon their peripheries with channels that are parallel to the axis of the brush, and I remark that the body or axis of the brush is usually of wood, and the ends A of the sweeper-box are notched, so that the brush can be introduced into place, and the journals 2 are either sprung into the bearings upon the end frames or inserted previous to screwing up one of the end frames. As an additional means for causing the pairs of actuating-wheels D to grip and rotate the pulleys E of the brush, I support the actuating-wheels D upon spring-axes formed at the ends of the coiled springs F. It is to be understood that there is a coiled spring at each end of the machine, and the middle part of each coiled spring is fastened to the inner surface of the end frame C, preferably by projecting ears or lugs 5, which are bent over to clip the middle portion of the spring after such spring has been inserted between such lugs, and the end portions of the coiled spring are wound similar to volutes, and then the portion 6 of each spring forms an axis for one of the actuating-wheels D. Hence it will be apparent that when the box of the sweeper and the frames C are pressed toward the floor the coiled springs F yield, and in so doing the axes 6 are drawn by the springs toward the pulley E of the brush, and thereby a greater force or pressure is exerted by the actuating-wheels against the pulleys E to obtain the requisite friction to rotate the latter. The handle G is secured into the socket 7 of the bail H, and this bail at its lower ends is turned inwardly to form pivots 8, which are received into slots in the end portions A of the sweeper-box, and this bail and handle can be swung over to either side of the sweeper, as usual, and when turned up vertically such bail and handle may be held from falling over by a spring-bow I, fixed upon one or both ends of the sweeper-box and adapted to receive a pin 9 on the bail H, such spring-bow being bent downwardly at its center portion to receive such pin 9 when the bail stands vertically.

Difficulty has heretofore been experienced in sweeping the carpet or surface and throwing the dust and particles of foreign matter up into the pans, because the edges of the pans have been at some little distance above

the floor. One feature of my present sweeper relates to movable inclines K, up which the dust is swept by the brush, and which movable inclines are either raised or lowered, 5 according to the direction in which the sweeper is being moved—that is to say, the brush where it is in contact with the carpet is rotating in the same direction as the sweeper and the incline at the front side is 10 brought down upon the surface of the carpet, or nearly so, in order that the dust may be caught upon such incline and carried up into the pan, and the incline behind the brush is raised up out of the way, so as not to be 15 injured. The movable inclines rest at their backs against the cross-bars L, and there are projecting studs 10 at the ends of the inclines, and these studs are received by the ends of the bent levers M, which are pivoted 20 at 11 upon the ends A of the sweeper-box, and such bent levers extend up with nearly vertical ends 12 at opposite sides of the pivots 8 of the bail, and such bent levers are connected by links 13. Hence such bent levers M are acted upon by the pivots 8 of the 25 bail and raise one of the movable inclines K and press down the other of such movable inclines, according to the direction in which the sweeper is being moved, as illustrated in Fig. 30 1, in which instance it is presumed that the sweeper is being moved in the direction of the arrow, and the brush will also be rotated in the direction of the arrow upon it, and the dust will be carried up the incline shown 35 sectionally in said Fig. 1, the other incline, which is indicated by dotted lines, being raised up out of the way, so as not to be injured by the movement of the sweeper. At the upper edges of these inclines teeth are 40 provided, as shown at 14, the object of these teeth being to comb off from the bristles of the brush any hairs, lint, or other substances that might otherwise adhere to the brush and finally interfere with its usefulness, and upon 45 reference to Fig. 1 of the drawings it will be observed that the bristles of the brush are moving toward the teeth 14 of the movable incline, which is elevated and shown by dotted lines, and these teeth are cleaning such 50 brush, and the brush is simultaneously cleaning the teeth of the other incline, which is shown sectionally, because the bristles of the brush are moving from the butts toward the points of the teeth, and of course these operations are reversed when the sweeper is moved 55 in the opposite direction, the teeth of one incline serving to free the brush from foreign substances, while the teeth of the other incline are being cleaned of accumulations by 60 the brush. By making the sides of the bars L that are next to the inclines K concave the said inclines slide thereon in the arcs of circles.

Between the cross-bars L and the sides A² 65 of the sweeper-box the dust-pans N are provided, each dust-pan being pivoted at each end by the screws or studs 15, so that such

pans can assume the positions shown by full lines in Fig. 1, or such dust-pans can be swung into the inclined position indicated by the dotted lines at 16, and there are springs O to act upon the dust-pans and retain them in their normal positions for use, and the dust-pans can be swung by the yoke-piece P and links Q, that are pivoted from the ends of the yoke-piece to the respective dust-pans, and upon the yoke-piece is a finger-piece P', extending up through a mortise in the top of the sweeper-box, so that by grasping the finger-piece and drawing it and the yoke-piece upwardly the dust-pans will be swung open for the contents to drop out with freedom, and when the finger-piece is liberated the springs O return the dust-pans to their normal positions, and it is advantageous to make use of 85 a catch 17, adapted to hold the yoke-piece and the finger-piece with the pans open. This catch 17 may be upon one side of the finger-piece P' to hook over the top of the sweeper-box at the mortise in the same, so as to retain 90 the finger-piece when the pans are opened. It is advantageous to make the sides of the cross-bars L that are adjacent to the dust-pans as concave curves struck from the pivots 15, so that the dust-pans can swing freely 95 when being opened; but dust will not pass in between the pans and the cross-pieces, and the swinging outer edges of the pans close up into rabbets 18 upon the lower edges of the sides A² of the sweeper-box.

It is advantageous to provide rubber bands or strips R to form fenders to prevent injury to furniture by the sweeper, and to secure these rubber bands or fenders R in position I pass the ends of the rubber through mortises 19 in the end frames C and provide upon the ends of the rubber buckles 20, fastened to the rubber and hooking upon projecting pins 21 at the inside of the end frames C, so that when either rubber becomes broken or injured it may be 100 removed with facility, and by this means the rubber is securely held to the metal end frames C, so as to prevent the rubber slipping off, as frequently occurs when a band of rubber only is made use of passing entirely 105 around the sweeper-box. In cases where there have been movable inclines for the brushes to sweep against they have not received a positive motion, and hence the wrong one might be lifted and the other injured or 110 injure the carpet by scraping thereon. Swinging dust-pans have been used; but their movement was so limited that the dust often had to be removed by the finger at the risk of such pan closing and pinching the hand. In 115 the ordinary sweeper the pan is at such a height from the carpet that sand and gritty substances are not easily swept up and light substances—such as feathers—are often blown about by the wind from the revolving brush. These difficulties are rectified by my present 120 improvements. Springs have been used at the axles of the actuating-wheels; but they have either been in the box and liable to in- 125 130

terfere with the pan or else they were difficult to replace, if broken, because of passing at both sides of each wheel. In the present improvement the wheels, being received on the ends of the spring, can be easily removed or replaced and the spring properly bent or a new one substituted with facility.

5 In my improvement the sweeping-incline that is raised up comes in contact, or nearly so, at its upper edge with the brush, and in so doing intercepts the air-currents, so that dust and light substances are not carried down and out of the box.

I claim as my invention—

15 1. The combination, in a carpet-sweeper, of the brush B, its pulleys E, the actuating-wheels D, the wire springs F, coiled as volutes and having at their ends the axes for the wheels, and the connections for the springs to the 20 end frames of the carpet-sweeper, substantially as set forth.

25 2. The combination, with the brush in a carpet-sweeper and the wheels for revolving the same, of dust-pans, movable inclines up which the dust is swept, and connections to such inclines and between the same and the bail of the sweeper, whereby the inclines are raised and lowered, respectively, according to the direction in which the sweeper is being 30 moved, substantially as set forth.

3. The combination, with the sweeper-box, the brush, and the dust-pans, of movable inclines, the handle and bail for giving motion

to the sweeper, and the bent levers between the ends of the bail and the movable inclines 35 for raising and lowering such inclines, substantially as set forth.

4. The combination, in a sweeper, of a brush and actuating-wheels for rotating the same, dust-pans, pivots for connecting such dust-pans to the box of the sweeper, springs for closing the dust-pans, a yoke and finger-piece, and links extending from the yoke to the dust-pans for opening such dust-pans for the discharge of the contents, substantially as set 45 forth.

5. The combination, in a carpet-sweeper, of a box, a brush within the box, actuating-wheels and pulleys, end frames outside of the wheels and pulleys, spring-supports for the 50 actuating-wheels, movable inclines and levers for actuating such movable inclines, and a bail for giving motion to the sweeper and raising and lowering the movable inclines, substantially as set forth.

6. The combination, with the box in a carpet-sweeper and the end frames, of the rubber strips passing at their ends through mortises in the end frames, and connections for the 55 ends of the rubber bands within the frames, substantially as set forth.

Signed by me this 2d day of March, 1891.
EDMUND E. PECK.
